GAS MIXING DEVICE

Elwood T. Larkin, Eggertsville, N. Y., assignor to
Charles A. Criqui, Buffalo, N. Y.

Application April 14, 1932. Serial No. 605,219

11 Claims. (Cl. 48—180)

This invention relates to devices for mixing two gases in desired proportions to each other, as may, for example, be necessary in connection with internal combustion engines or other devices to which gas mixtures may be fed. Gas mixing devices, as heretofore made, have been adjustable to operate only within a limited range of proportions. Consequently, if a proportion of the two gases beyond such range was required, another mixing device or valve had to be supplied. When devices of this kind are used in connection with internal combustion engines, these devices are sometimes required to operate on gases differing widely in quality. It is also desirable with engines of this kind to provide means whereby an engine can be quickly changed over to operate on liquid instead of gaseous fuel, as may, for example, be the case where an engine is operating on a gas supply which is not available at all times.

The objects of this invention are to provide a gas mixing device by means of which a wide variation in the proportions of two gases may be obtained and with which one of the gas supplies may be entirely interrupted; also to provide a device of this kind, which is so constructed as to produce a constant and accurately proportioned mixture of gases under different rates of supply of the gases; also to provide a gas mixing device of this kind for mixing air and gas and in which the gas is supplied at a pressure not substantially exceeding atmospheric pressure; also to provide a gas mixing valve with a throttle valve of improved construction; also to provide a gas mixing valve with means for quickly and accurately adjusting the valve for the proportions of the two gases desired; also to provide a valve of this kind with improved means for locking the same in its adjusted position; also to provide a valve of this kind with means for indicating when the valve is set for producing a mixture of the desired proportions; also to provide a valve of this kind with a deflector for effecting a more complete mixing of the two gases; also to improve the construction of gas mixing devices of this kind in other respects hereinafter specified. The gas mixing device is illustrated in the accompanying drawings for use in connection with internal combustion engines, but it will be understood that it is not intended to restrict the device for use in connection with engines since obviously the device can be used

wherever a mixing of two gases is desired in definite proportions.

In the accompanying drawings:

Fig. 1 is a side elevation of an internal combustion engine having a gas mixing device embodying this invention applied thereto;

Fig. 2 is an end view of the mixing valve on an enlarged scale;

Fig. 3 is a transverse sectional elevation thereof, on line 3—3, Fig. 6;

Fig. 4 is a transverse sectional elevation thereof, on line 4—4, Fig. 7;

Fig. 5 is a longitudinal sectional elevation of the gas pressure regulating device shown in Fig. 1;

Figs. 6 and 7 are longitudinal, central sectional elevations of the mixing valve, showing the parts thereof in different positions.

A represents an internal combustion engine, which may be of any suitable construction, and which has a gas inlet passage *a* to which a combustible mixture is to be supplied. B represents in general a gas mixing valve, which supplies a combustible mixture to the gas inlet passage *a* of the engine. Air is ordinarily admitted to the mixing valve B through an inlet duct or elbow 10 containing a choke valve 11, Fig. 7, operable by means of a crank or arm 12, Fig. 1. C represents a carburetor, which may be used when the engine is run on gas, the carburetor and connections shown in broken lines in Fig. 1 are entirely detached so that air for mixing with gas can enter the open end of the air intake duct 10. 15 represents the gas inlet duct of the mixing valve B to which gas may be conducted through a passage 16 and connected with an accumulator or reservoir 17 containing the gas at a reduced pressure, the gas originally being received under pressure through a pipe 18 leading to a pressure reducing valve D.

The mixing valve itself, in the particular construction illustrated, has a substantially cylindrical housing 20 formed at its upper side of its cylindrical wall with a discharge passage 21 and a flange 22 arranged about this passage serves to connect the mixing valve with the air intake passage *a* of the engine. The pipe or gas duct 15 may be connected with a threaded nipple 24 formed integrally on a side of the mixing valve B and the gas, in the construction shown, enters the housing 20 of the valve through an opening 25 therein, a passage 26 in the valve housing connecting the threaded nipple 24 with the opening 25. The ends of the

cylindrical housing 20 may be closed by end covers or plates 27 and 28 secured in any suitable manner to the cylindrical housing, for example, by means of bolts or screws 29, Fig. 2. 5 30 represents the air intake passage or opening in the cylindrical housing 20 through which air enters the interior of the mixing valve from the inlet duct 10.

The combustible gases which may be used in 10 connection with internal combustion engines differ greatly in quality, some of these gases being as low as 100 B. t. u.'s per cubic foot, whereas other gases contain as much as 1500 B. t. u.'s per cubic foot. In order to provide for the desired 15 ratio of the two gases entering into the housing 20, means are provided for constricting one of the two inlet openings while enlarging the other. In the construction shown for this purpose, a 20 proportioning member 32 is provided which is in the form of a cylinder arranged to be adjusted lengthwise within the cylindrical housing 20. This proportioning member or cylinder is provided with an air opening 33 and a gas opening 34. The air and gas openings 33 and 34 are 25 approximately of the same sizes respectively as the air passage 30 and of the gas opening 25 in the valve housing, but the openings 33 and 34 are so arranged that when the opening 33 is in full registration with the air inlet passage 30 30 so as to admit the maximum air, the gas opening 34 will be entirely or almost entirely out of registration with the gas opening 25 so that the passage of gas into the mixing valve is interrupted, as shown in Fig. 7. When the proportioning member 32 is moved to the left, the 35 size of the air passage through the inlet 30 and opening 33 is reduced and a corresponding increase results in the size of the gas opening, in proportion to the extent to which the member 40 32 is moved to the left, Fig. 6 showing the gas opening almost unobstructed and the air passage reduced to almost half of its maximum size. The proportioning member is provided in its opposite side with a relatively large discharge 45 opening 35 which registers with the discharge passage 21 during all positions of the proportioning member 32, so that the discharge passage for the mixture is not interrupted or decreased in size in any position of the proportioning member.

Any suitable or desired means may be employed for adjusting the position of the proportioning member or valve 32. In the particular construction shown, a screw threaded stem or 55 bolt 37 is secured at its inner end to the proportioning member 32, for example, by means of a screw or pin 38, and extends out through the end cover or plate 28 at one side of the mixing valve. This screw 37 engages an internally threaded sleeve 39 having a hand wheel 40 secured to the outer end thereof, for example, by means of a threaded engagement with the sleeve 39 and a pin 41, and the sleeve 39 has at its inner end an outwardly extending flange 42 or projection 42 engaging at its inner side on an inwardly extending flange or annular bead 43 of the end or cover plate 28. In order to hold the sleeve 39 against endwise movement during the turning of the same, a gland nut 45 is provided having a central bore or aperture into which the sleeve 39 fits snugly. The outer surface of this gland nut is threaded and engages a correspondingly internally threaded boss 46 formed on the end cover member 28. The flange 75 42 of the sleeve 39 engages the inner end of the

gland nut 45 so that outward movement of the sleeve is prevented by the gland nut. Consequently, by turning the sleeve 39 in either direction, a corresponding movement of the proportioning member 32 results. When the proportioning member has been adjusted to the desired position, the gland nut 45 may be turned in a direction to clamp the outwardly extending flange 42 of the sleeve 39 against the inwardly extending flange 43 of the end cover member 28, and thus secure the sleeve 39 against turning, which in turn prevents any change in adjustment of the proportioning member 32 until the gland nut is again released. Any other means for adjusting the proportioning member 80 and for locking the same in its adjusted position may be employed, if desired.

The mixing valve is also provided with a throttle which is arranged to act on the incoming air and gas passages to vary the amount of 85 air and gas admitted through these openings, and thus to control the speed of the engine when the mixing device is used in connection with an engine. The throttle valve, in the construction shown, includes a substantially semi- 90 cylindrical portion 48 adapted to fit within the cylindrical proportioning member 32, and is also provided with radially extending end webs or parts 49 and 50, preferably formed integrally with the cylindrical portion 48 and suitably secured to a central shaft 51, for example, by means of taper pins 52. This shaft is journaled in bearings 54 suitably arranged in the opposite end cover members 27 and 28, roller bearings being shown in the construction illustrated. 95

The semi-cylindrical portion 48 of the throttle valve is provided with an opening 56 which is adapted to register with the air passage 30 in the cylindrical member 20 and an opening 57 adapted to register with the gas opening 25 in the housing 20. Consequently, it will be obvious that by turning the shaft 51 and the throttle valve in either direction from the position shown in Fig. 4, the passages for air and gas will be decreased, and the decrease in these passages will be in the same proportion in both passages. The turning of the throttle member is entirely independent of the adjustment of the proportioning member 32, so that by changing the position of the throttle member, the proportion 105 of gases in the mixture discharged from the mixing valve will not be changed. By means of the arrangement of the throttle member as described, the suction of the engine acting on the semi-cylindrical throttle member when the same 110 is partly closed, will tend to move the throttle member out of contact with the cylindrical surface of the proportioning member 32, so that friction between these two members is avoided. This is particularly desirable when the operation of the throttle member is controlled by a governor which has very little power by means of which the throttle valve is turned.

The end webs 49 and 50, in addition to supporting the throttle valve from the shaft 51, also 115 act as deflectors for controlling or directing the flow of gas through the interior of the valve, keeping the gas from flowing into the end portions of the mixing valve, and thereby reducing the resistance to flow of the gases through the 120 mixing valve.

Internal combustion engines are sometimes operated in plants where a supply of gas is not at all times available, for example, in plants where the gas used may be a by-product of some manu- 125

facturing process. In such cases, it is desirable to operate the engine on liquid fuel, if gas is not available. By means of the mixing valve described, this can be easily done by moving the proportioning member 32 into the position shown in Fig. 7 in which the gas supply is entirely interrupted and the air valve is wide open. In such cases, a carburetor C of any suitable construction can then be attached to the air intake duct 10. In order to enable the proportioning valve member 32 to be quickly placed into a position to operate on gas, when gas again becomes available, means are preferably provided to indicate when the proportioning member 32 has been returned to its correct position. Any suitable means may be employed for this purpose, and in the construction shown, the end cover member 28 is provided with a threaded aperture in which a bolt 60 engages. When the proportioning member has been set into the correct position for the particular gas on which the engine is to operate, this bolt 60 is turned until the end of the bolt engages the proportioning member 32 as shown in Fig. 6, whereupon the bolt is locked in this position by means of a lock nut 61. Consequently, when the proportioning member has been moved into the position shown in Fig. 7, it can be quickly restored to the correct position by turning the hand wheel 40 until the proportioning member strikes the stop bolt 60. The position of the proportioning member 32 can also be determined by the end 62 of the screw 37, which occupies different positions of the proportioning member as may readily be seen by comparing the position of this end 62 in Figs. 6 and 7.

In order to provide for a more thorough mixing of the air and gas, the throttle valve is preferably provided with a baffle 63, the lower end of which is secured to or formed integrally with the semi-cylindrical portion 48 of the throttle valve at a point between the openings 56 and 57 therein, and this baffle 63 preferably extends diagonally over the air opening 56. The baffle is provided with a relatively large aperture or central opening 64 through which the shaft 51 extends. This baffle divides the air entering into the mixing chamber so that a part of the air flows through the opening 64 therein and mixes with the gas immediately after the gas enters the mixing chamber. Another part of the air is deflected by the baffle member 63 toward the upper portion and sides of the mixing valve, and then flows across the edge of the baffle in a direction more or less crosswise of the current of gas which has been mixed with the primary current of air flowing through the opening 64. By supplying the air to the gas in two streams mixing successively with the gas, or with different portions of the gas stream, a very thorough mixture of gas and air has been found to result, so that better combustion of the mixture takes place. A mixing baffle of this kind is preferably, though not necessarily, used in connection with the mixing valve.

The shaft 51 of the throttle valve, in the construction shown, is provided at one end beyond the end or cover plate 27 with an arm 66 suitably secured to the shaft, and a link 67 is shown pivotally connected with the outer end of this arm. This link may be actuated through a bell crank lever 68, and another link 69 from any suitable control device, such for example as a governor or a hand control, or both governor and hand controls may be employed, which may

be connected with the throttle valve shaft by suitable independently operable means, not shown.

Means are preferably also provided for limiting the extent to which the throttle valve may be moved, and for this purpose, the end of the shaft projecting through the end plate 28 is provided with a clamp 70 which may be secured on the shaft by means of a clamping screw or bolt 71, and which has arms 72 and 73, one of these arms, for example, the arm 73, having an adjustable stop bolt 74 extending through a threaded hole in the arm 73 and arranged to be locked in its adjusted position by means of a lock nut 75. The stop arm 72 and bolt 74 of the other arm 73 are adapted to engage with opposite sides of a fixed stop projection 76, which, in the construction shown, is in the form of a lug or part formed on the end plate 28. Any other means for limiting the movement of the throttle valve may be employed.

In the operation of internal combustion engines from a source of gas supply by means of a mixing device of the kind shown, if the gas is supplied to the mixing valve under pressure, trouble is frequently experienced in starting the engine because of too much gas accumulating in the mixing valve and intake manifold because of the pressure of the gas. This results in a mixture which is too rich to ignite. Furthermore, with a valve of the kind shown, the pressure of the gas as well as the quality of the gas, would have to be taken into consideration in adjusting the proportioning member 32. I have found that the operation of the mixing device can be simplified and made more satisfactory, particularly when the mixing valve is used in connection with an internal combustion engine, if the gas is supplied to the mixing valve at not substantially more than atmospheric pressure. Under such conditions, the suction of the engine will draw into the mixing valve uniform proportions of air and gas, regardless of variations in suction resulting from variations in engine speeds. For this purpose, a pressure reducing valve D is preferably employed, and which is so set or designed that the pressure of the gas entering the reducing valve from the pipe 18 is reduced to approximately atmospheric or subatmospheric pressure before passing into the supply reservoir or accumulator 17. This reducing valve may be of any suitable or usual construction, that shown in Fig. 5 having the usual housing 30 provided with a passage 31 therein controlled by a valve 32 secured on a stem 33. This stem is suitably connected to diaphragms 34 and 35, the diaphragm 34 being acted upon on its entire upper surface by atmospheric pressure entering the diaphragm chamber 36 through apertures 36a and on its under surface by pressure in the receiver or cylinder 17 which enters into the diaphragm chamber 36 through a small passage or duct 37. The under face of the diaphragm 35 is acted upon by the pressure of the gas entering the regulator 140 through the pipe 18. Any other pressure reducing means may be provided, if desired. 39 represents a gas shut-off cock in the pipe 16.

When the engine is started, increased richness of the mixture may be obtained by manipulation of the choke valve 11, but excessively rich mixtures are avoided because the pressure of the gas supplied to the mixing valve is low. Preferably, the gas supplied at atmospheric or below atmospheric pressure, but pressures slightly

exceeding atmospheric pressure may be used without departing from this invention. The gas valve described has the advantage that it is easily adjustable, and has such a wide range of adjustment that it can be used in connection with any gas now available for operating an internal combustion engine, regardless of its quality, the adjustments ranging from equal parts of air and gas to a zero quantity of gas when the parts are in the position shown in Fig. 7. If the quality of the gas changes, it is an easy matter to adjust the mixing valve to operate on a different gas. The arrangement of the proportioning member 32 and the throttle member is such that adjustments of the proportioning member have no effect upon the throttling member, so that any position of the throttling member produces the same throttling effect, regardless of the position of the proportioning member.

I claim as my invention:

1. A gas mixing valve, including a housing having gas inlet openings formed therein, a member movable relatively to said housing and having parts adapted to cooperate with said openings to decrease one of said openings while increasing the other opening, and a valve member movable to different positions with reference to said openings to simultaneously restrict both of said openings to approximately the same extent.

2. A gas mixing valve, including a housing having gas inlet openings formed in one side thereof and a gas discharge opening in another side thereof, a member movable relatively to said housing and having openings therein corresponding in size to said inlet openings, said openings being spaced apart so that when one of said openings is in full registration with an opening in said housing, the other opening in said movable member substantially closes the other inlet opening in said housing, and a throttle member having openings adapted to register simultaneously with said inlet openings in said housing and adjustable crosswise of the direction of adjustment of said first mentioned member for throttling the passage of gases through said inlet openings.

3. A gas mixing valve, including a substantially cylindrical housing having gas inlet openings formed in a side thereof and a gas outlet opening in another side, a cylindrical member arranged within said housing and adjustable therein and having an opening registering with said outlet opening, openings adapted to cooperate with said inlet openings in said housing and spaced so that adjustment of said member to decrease the passage through one of said inlet openings results in increasing the passage through the other opening, and a throttle member also arranged within said housing and having a surface of cylindrical curvature cooperating with the apertures of said housing and first mentioned member for controlling the passage of gases through said openings.

4. A gas mixing valve, including a substantially cylindrical housing having gas inlet openings formed in a side thereof and a gas outlet opening in the opposite side thereof, a cylindrical member arranged within said housing and adjustable lengthwise therein and having an opening registering with said outlet opening throughout all adjustments of said member and having openings adapted to cooperate with said inlet openings to change the proportions of the

passages through said openings relatively to each other, and a throttle member arranged within said housing and of substantially semi-cylindrical form and cooperating with said inlet openings of said cylindrical member, whereby pressure of gas entering said opening tends to move said throttle member out of contact with said cylindrical member.

5. In an air and gas mixing valve having separate inlet openings for air and gas, the combination of a throttle valve provided with openings adapted to register with said inlet openings and having a part movable crosswise of said inlet openings to throttle the same, a pivot about which said throttle member is movable, whereby suction within said valve tends to move said throttle member out of frictional contact with said valve.

6. A gas mixing valve having a substantially cylindrical housing provided with gas inlet openings in one portion thereof and a discharge outlet for a mixture of gases in another portion thereof, a substantially cylindrical member arranged inside of said housing to move lengthwise therein and having air and gas openings adapted to cooperate with said inlets in said housing to cover one of said inlets while uncovering the other inlet, said member also having an opening in registration with said outlet, means for adjusting said cylindrical member lengthwise of said housing for varying the proportion of gases passing through said inlets, a throttle valve of substantially semi-cylindrical form arranged within said cylindrical member and movable crosswise thereof and having apertures arranged to register with said inlets in said housing for controlling the discharge of air and gas through said inlets.

7. A gas mixing valve having a substantially cylindrical housing provided with gas inlet openings in one portion thereof and a discharge outlet for a mixture of gases in another portion thereof, a substantially cylindrical member arranged inside of said housing to move lengthwise therein and having air and gas openings adapted to cooperate with said inlets in said housing to cover one of said inlets while uncovering the other inlet, said member also having an opening in registration with said outlet, means for adjusting said cylindrical member lengthwise of said housing for varying the proportion of gases passing through said inlets, a throttle valve of substantially semi-cylindrical form arranged within said cylindrical member and movable crosswise thereof and having apertures arranged to register with said inlets in said housing for controlling the discharge of air and gas through said inlets, and a baffle on said throttle valve extending partially across one of said inlet openings and having an aperture through which a part of one of said gases can pass for mixing with the other gas, another part of said first gas passing around the edge of said baffle.

8. A mixing valve having a substantially cylindrical housing provided with gas inlet and outlet openings, a cylindrical proportioning member slidable lengthwise within said housing for cooperating with said inlet openings to control the proportions of gases entering said housing, a throttle member arranged within said cylindrical member and having a cylindrical portion provided with passages for throttling the flow of gas through said housing, and cover members secured to said housing for closing

the ends thereof, a shaft journalled in said end cover members and to which said throttle is secured, and means on said end cover member for regulating the position of said proportioning member within said housing.

9. A gas mixing valve, including a substantially cylindrical housing having gas inlet openings formed in a side thereof and a gas outlet opening in the opposite side, a proportioning member cooperating with said inlet openings to vary the proportions of gases entering said housing, a throttle member within said housing and adjustable about an axis in said housing, and having a part arranged to cooperate with said proportioning member for controlling the quantity of gases entering said housing, said throttling member also having webs extending cross-wise of said cylindrical housing for directing the flow of gas toward said outlet opening.

20 10. A gas mixing valve including a housing having a cylindrical bore and having gas inlet openings formed therein, a cylindrical member arranged in said housing and movable length-wise therein and having parts adapted to co-

operate with said inlet openings to decrease one of said openings while increasing the other opening, and a valve member also arranged in said housing and movable approximately about the axis of said cylindrical bore to different positions with reference to said openings to simultaneously vary the discharge of gas through both of said openings.

11. A valve for use with either gaseous or liquid fuel, including a housing having air and gas inlet openings formed in a side thereof, a proportioning member cooperating with said inlet openings to vary the proportions of air and gas entering said housing and arranged to entirely close said gas inlet opening when said air inlet opening is wide open, a single throttle member cooperating with both of said inlet openings for simultaneously restricting both of said openings, and means for connecting a liquid fuel carburetor with said air inlet opening, whereby said throttle member serves to control combustible mixtures of other gaseous or liquid fuel.
